James. L. Dorward.

INVENTOR.

UNITED STATES PATENT OFFICE.

JAMES L. DORWARD, OF SAN FRANCISCO, CALIFORNIA.

NECKTIE HOLDER.

Application filed August 28, 1919. Serial No. 320,483.

To all whom it may concern:

Be it known that I, JAMES L. DORWARD, a subject of Great Britain, residing in the city and county of San Francisco, State of California, have invented certain new and useful Improvements in Necktie Holders, whereof the following is a specification.

This invention relates to improvements in necktie holders, of the character which renders it unnecessary to pass the tie around the neck. One of the improvements, may, however, be used for other purposes where a bow is required; this part is called a tie carrier for holding a handtied bow.

The several improvements embraced in this invention can be used separately, and with some existing tie holders, but all of them should be used together, making a much desired combination.

The combined object of this invention is to produce in a simple device separable from a collar, a means ready at hand for the optional formation of a hand formed bow tie in particular and other kinds of ties in general; and their easy attachment, detachment and substitution one for the other; and the fixing of any one of same, in any position desired, upon any ordinary turned down collar in common use; thus accomplishing and imitating by the mechanism of one device, all the combined optional and desirable functions of ordinary neck band ties used directly around ordinary turned down collars; with the elimination of the resultant disadvantages thereof, such as the trouble of repeated tying and untying of knots, sticking of the neck band around the collar, consequent wear and tear of tie material, soiling of collars, and loss of time in forming and applying.

One object of this invention is to produce a necktie holder, which, by being unnoticeable as regards its exposed part enables an attached tie to be worn higher than the collar button.

Another object of this invention is to produce a natural hand tied bow necktie which can be worn without the trouble of tying and untying it, each time it is required, and another object is, to provide a tie holder with a means to prevent itself from tilting, thus keeping the tie plumb or horizontal, according as to whether a four in hand, or bow tie is used.

A further object is to produce a tie holder that is changeable in size, so that it can be

easily adapted for use with either high or low ordinary turned down collars; with the further object in view of fixing the position of a preformed tie prior to its attachment to a collar, so that the tie becomes located in the desired particular position, simultaneously with its quick and easy attachment to any ordinary turned down collar, which may be already fastened around the neck of the wearer.

Another object is to provide a means whereby various forms of ties as well as a particular kind of bow described herein, can be formed on a single device, thus saving the employment of a plurality of tie carriers for accomplishing the same purposes.

The foregoing objects will be apparent from the subjoined description of the drawing, in which the same is illustrated in two sheets, showing an embodiment thereof as it would appear when constructed of sheet material. For clearness of description, a carrier is that part of a tie holder which carries a tie, and a holder is that part which holds the carrier and has a means of fastening to a collar button.

Figure 1 is a necktie holder, showing fabric impressions.

Figure 2 is a back view of a necktie holder showing the anti-tilting lugs, 5.

Figure 3 represents the front part of a collar, viewed from the inside of same, and showing the anti-tilting lugs, 5, of the holder, engaging the bottom edge of the collar.

Figure 4 is a sectional elevation of the holder.

Figures 5, 7, 8 and 9 are views of some modifications of the tie carrier. Figure 6 is a circular member for forming bows only.

Figure 10 is a front elevation of a tie carrier as is used with a necktie holder.

Figures 11 and 12 illustrate a method of tying a bow on the tie carrier.

Figure 13 shows a back view of the tie carrier and bow.

Figure 14 shows a holder with a carrier with its concave edge uppermost, as for use with a low collar.

Figure 15 shows a back elevation of a holder with the carrier reversed, its convex edge being uppermost, as for use with a medium height collar, and shows the alternative fastening points, 9.

Figure 16 shows a front elevation of a necktie holder with the carrier fixed in the top position, for use with a high collar.

Figure 17 is an elevation of a modified device consisting of the holder and carrier combined in one piece.

Figure 18 shows a tie holder complete with the bow in the position as worn with a high collar.

10 An outstanding feature in previous designs of necktie holders of the class which comprise a form shaped to engage under the fold of a turned down collar, is invisibility when in use, which has been accomplished by hiding the tie holder behind the tie, with the resultant drawback that the tie could not be worn at any desired height above the collar button, as shown performed in Fig. 18, where 6 is the holder member; this 20 desirable result is accomplished by making the holder unnoticeable, even when visible, by having impressions upon its surface showing below the tie carrier as seen in Figure 18, resembling the make and material of the collar with which it is worn, and, for this purpose, it is made of celluloid, or similar plastic material, so as to lend itself to such impressions. Although a bow necktie holder is shown in the drawings, 30 this part of the invention, namely, the fabric impressions on this tie holder applies to all types in the aforementioned class of necktie holders which fasten to the collar button, as the lower part of the holder 35 can sometimes be seen by a side view, even when a four in hand tie is used.

In Figure 1 will be seen a tie holder having such impressions, which may, however, to accomplish the above object be limited 40 only to that part of the surface which will be exposed when in use, 1, indicates the surface impressions resembling fabric material, 2, the impressions resembling stitching near the edges, 3, impressions resembling stitching 45 around the button hole, and 4, impressions of a margin, similar to that which appears on newly ironed textile fabric material, and caused by the extra thickness of the hemming.

50 To prevent the tie holder from tilting, anti-tilting lugs or projections, 5, engage the bottom inside edge of the collar, 7, as seen in Figure 3, thus preventing the holder, 6, from tilting on the collar button and tending 55 to keep the tie straight. The numeral 8 indicates the outside fold of the collar.

To form a natural handtied bow necktie which does not require untying and retying each time it is used, the tie carrier, some 60 modifications of which are illustrated in Figures 5, 7, 8, 9 and 10, is employed; this consists simply of a longitudinal member formed with a central aperture 11. This aperture should be of such a size and construction as will permit the two ends of the

center binding loop A, see Figs. 11 and 13, to pass through, and be gripped together, and the tie material crimped on both sides towards the center of the opening, thus providing a means of keeping the bow knot 70 tight and natural in appearance. A circular opening is shown as being the simplest to manufacture, but it may vary in shape providing it has the quality of holding the tie material squeezed in a centripetal manner. 75

The central binding loop, A, is shown formed in Figure 11, on the carrier, C, with the ends of the tie extending on each side, the said ends being next doubled and passed 80 through the loop, A; Fig. 12, shows one end through and the other end, B, about to be passed through.

Figure 13 shows a back view of the tie carrier and bow, and by providing the 85 former with suitable means of attachment, it can be used either as an article of adornment; or in dress wear, such as a hat, waist band, hair dress, or for any other purpose where a bow can be used. 90

In using the tie carrier for neck wear, it is best to have it of longitudinal form and curved as illustrated in Fig. 10; the length of its upper edge provides a support for four in hands and other forms of ties, and 95 having also a single central opening, of the character previously described, located between its opposed top and bottom edges, the hereinbefore described bow can also be formed on this same device; thus enabling 100 the user thereof to form various ties on this single carrier which hitherto would necessitate the use of two carriers to accomplish the same objects. The length of this member also provides a novel means of using this 105 bow for neckwear, as the fastening points or means being attached to the ends of said member, are necessarily wide apart, with the advantage of being well out of sight, see Fig. 18; this distance between the fastening 110 points also provides for a free and clear space behind the middle part of said tie carrier, which facilitates the wrapping of tie material around same.

Fig. 14, shows the tie carrier fastened in 115 the lowest position which is suitable for wear with a low collar. Snap fasteners may be used as an attaching means.

The fastening points, 9, of the carrier shown in Fig. 10, it will be noticed, are in 120 a relatively higher horizontal plane than the aperture, consequently if the carrier is fixed to the top fastening points with its convex edge uppermost, as at Figure 16, the position is suitable for a high collar. Intermediate and lower heights can be attained by utilizing intermediate and lower fastening points in the holder or by reversing the carrier as shown in Figures 14 and 15, or by any other means. Although only two 130

pairs of fastening points are shown, it is obvious that a greater range of adjustment can be obtained by adding extra pairs of fastening points having the same horizontal spacing between the units comprising each pair.

Figure 17 is an alternative one piece device for holding a bow tie, but is incapable of adjustment, and for this reason cannot be used with a low collar; it has, however, the aperture, 11, which is one of the important features of this invention, and being integral with the holder, requires a slit, 12, below the aperture, of just sufficient size to permit one end of the tie to pass through, to facilitate the tying of the bow.

Figure 18, shows a necktie holder in use, the holder and carrier assembled as at Figure 16, with a hand tie bow attached as previously described. A part of the holder, 6 is exposed to view, and has upon this exposed part the fabric impressions 1, imitation stitching 2, along the edges, imitation stitching around the button hole 3, together with the raised margin of the hem 4. In this way it is quite unnoticeable and feigns to be a part of a collar 8. This feature, it will be noticed, enabling the user thereof to fix the tie at the top of the collar, without attracting attention to the fact that a tie holder of this class is being used.

Having thus described my invention, what I claim as new and useful is;

1. The combination in a neck tie holder, of a holder member comprising a form adapted to engage between the folds of a turned down collar, and separable therefrom, a tie carrier extending across the

front of said holder member in a manner to provide a free passage behind the middle part of said carrier, and means of fixing said carrier to said holder member in different positions of adjustment. 40

2. In a neck tie holder, a holder member comprising a form adapted to be fastened on a collar button and under the outside fold of a turned down collar and separable therefrom, and provided with a plurality of superimposed pairs of equally spaced fastening points. 45

3. The combination in a neck tie holder, of a holder member consisting of a form adapted to engage under the outside fold of a turned down collar and separable therefrom, a tie carrier comprising a member having centrally between its upper and lower opposing edges a single opening constructed to hold tie material crimped in a centripetal manner, and means of connecting said members together in different positions relative to each other. 55

4. A neck tie holder, comprising a holder member consisting of a form adapted to engage under the outside fold of a turned down collar and separable therefrom, a tie carrier comprising a longitudinal member having centrally between its upper and lower opposing edges a single opening constructed to hold tie material crimped in a centripetal manner, and fastening means attached on the ends of said tie carrier and located in a different horizontal plane to the centre of the opening, for attaching said carrier to said holder in reversible positions. 60 65 70
